[57] CLAIM

The ornamental design for a baseball training article, as shown and described.

DESCRIPTION

FIG. 1 is a front elevational view of a baseball training article showing my new design;
FIG. 2 is a side elevational view thereof; the side opposite being substantially a mirror image;
FIG. 3 is a rear elevational view thereof;
FIG. 4 is a bottom plan view thereof; and
FIG. 5 is a top plan view thereof.
